DESIGN

J. F. VOLZ.

ORGAN CASE.

No. 15,624.

Patented Dec. 16, 1884.

Fig. 1.

Fig. 2.

UNITED STATES PATENT OFFICE.

JOHN F. VOLZ, OF CHICAGO, ILLINOIS, ASSIGNOR TO THE W. W. KIMBALL COMPANY, OF SAME PLACE.

DESIGN FOR AN ORGAN-CASE.

SPECIFICATION forming part of Design No. 15,624, dated December 16, 1884.

Application filed April 8, 1884. Term of patent 31 years.

To all whom it may concern:

Be it known that I, JOHN F. VOLZ, a citizen of the United States, residing in Chicago, in the county of Cook and State of Illinois, 5 have invented a new and original Design for Cabinet-Organ Cases, of which the following is a specification.

Figure 1 is a front view in perspective of my design. Fig. 2 is an end view of the same.

- 10. My design for an organ-case is surmounted by a canopy, A, having an arched center pediment-like ornament, a , presenting a foliated front, and supported upon side square pillars and intermediate turned spindles. The arch 15 of the ornament terminates at either side in rosettes. The canopy is also topped at either side of said center ornament by railings a' , extending along the ends and partly in front, such railing consisting of a rail, square posts 20 at each end, and intermediate turned spindles, the end of the rail in front projecting beyond the post and terminating in a scroll. Below the canopy is provided with a pendent finial and an ornament, a'' . At either side of the 25 book-pocket B are spaces inclosed at the back and outer end, the back of the inclosure being a close portion, b , having a rosette in the center, and surmounted by the balustrade b' and the ornament b'' . At the end are corner 30 and front posts, b^1 and b^2 , and between a balustrade having an upper section composed of rings b^3 and a lower section of spindles b^4 . The posts are capped by finials, as shown. At 35 either side of the music-rack C will be found lattice-like fretwork C' , having the inter-spaces filled by rings. At the ends adjoining these lattice-work panels are balustrades C^2 , which extend and are bent around upon the front, so that the end post is located at a small 40 remove from the end. Upon the end the case is recessed at d , the corners are rounded at d' ,

and the large plain surface D is relieved with longitudinal sunken moldings d^2 . Immediately below the balustrade b^3 b^4 b^5 b^6 , upon the surface D , is some engraved line ornamentation 45 d^3 . The key-board bracket E has the cut-line ornamentation e , below which are three rosettes, e' , and still farther down is a large rosette ornament, e'' , and other cut lines, e^3 .

I claim—

- 1. The design for a cabinet-organ case herein shown. 50
- 2. The design for an organ-case wherein the case is provided with a canopy-top, substantially such as shown. 55
- 3. In a design for organ-cases, the top consisting of the canopy and the book-pocket section, the same having the general configuration shown. 55
- 4. In a design for organ-cases, the book-pocket and the inclosures at the side thereof, all ornamented as shown. 60
- 5. In a design for organ-cases, the end of the case having the ornamentation and shape herein shown. 65
- 6. In a design for organ-cases, the music-rack section embracing a music-rack, fret-work panels C, and balustrades C^2 , having the ornamentation and shape herein shown. 70
- 7. The design for an organ-case wherein 75 the case is surmounted by the foliated pediment-like ornament a , and is otherwise configured and ornamented substantially as shown.
- 8. In a design for an organ-case, the key-board bracket E, configured, and having the ornamentation e , e' , e'' , and e^3 , substantially as shown. 75

JOHN F. VOLZ.
